CROWNED CUPPED RESILIENT PLUG FOR
CYLINDRICAL PASSAGES

Marshall L. Lockhart, Rutherford, N. J., assignor,
by direct and mesne assignments, to The Com-
pule Corporation, Rutherford, N. J., a corpo-
ration of New Jersey

Application May 9, 1950, Serial No. 160,987

11 Claims. (Cl. 128—220)

1

The present invention relates to plugs for cylindrical passages and, more particularly, to the type employed for stoppering tubular structures which may serve as a piston plug therein, and is adapted especially to use in medicinal storage vials, ampules, hypodermic injection syringes, etc.

A general object of the present invention is to provide such plugs from resilient material, generally of a crowned cupped shape, which are easily and economically mass produced and which permit use thereof efficiently as stoppers for tubular structures, as piston plugs for expelling fluids from ampule tubes and syringe barrels, or as partitioning means in tubes readily provided, if desired, with pierced slits effectively to serve as efficient one-way valves, i. e., permitting passage of fluids under pressure from within the cupped chambers in the plugs while blocking reverse flow; the crowned closure ends of the plugs being of such shape and so proportioned as to avoid any tendency to bulge laterally with in-folding to a degree that might tend to locate folds thereof laterally beyond edges of the holes or tubular structures in which they are mounted while permitting effective use as aspirating means.

A more specific object of the present invention is to provide such a crowned cupped resilient plug which has one end of a substantially cylindrical base sleeve section closed off by a relatively highly flexible domed closure and rendered relatively inflexible at its tip to provide between the latter and the sleeve section a relatively highly resilient zone so proportioned and disposed as to prevent undue lateral bulging thereof with in-folding under pressure applied either mechanically or by means of fluid so that folds thereof will not extend laterally an appreciable distance beyond the outer margins of the plug to overlap edges of the tubular structure when employed as a stopper in an end thereof.

Another object of the present invention is to provide such a crowned cupped resilient plug in which the domed closure end is readily pierceable to provide fluid passage slits which permit escape of fluid when pressure thereof is applied internally of the hollow plug and which may be effectively closed to passage of fluid when pressure thereof is applied to the outside of the domed end with resultant in-folding of the latter so that the plug may serve as a one-way valve; the stiffened tip of the domed closure end also being readily pierceable centrally thereof to permit passage therethrough of a withdrawing needle,

2

such as that of a hypodermic syringe, and in such case allowing use of the inherent action of the domed end with periodic application thereto and relief therefrom of pressure effectively to provide aspirating action.

5 A further object of the present invention is to provide structural embodiments of the plug of the present invention which may be readily made and allow efficient use and operation thereof for a variety of purposes, as will be more fully apparent from the following description.

Other objects of the invention will in part be obvious and will in part appear hereinafter.

The invention accordingly comprises an article 15 of manufacture possessing the features, properties, and the relation of elements which will be exemplified in the article hereinafter described and the scope of the invention will be indicated in the claims.

20 For a fuller understanding of the nature and objects of the invention, reference should be had to the following detailed description taken in connection with the accompanying drawing, in which:

25 Fig. 1 is an enlarged side view of an embodiment of the crowned cupped resilient plug of the present invention;

Fig. 2 is an end view shown in Fig. 1 as observed from the domed closure end thereof;

30 Fig. 3 is a longitudinal sectional view, taken substantially on line 3—3 of Fig. 2;

Fig. 4 is a sectional view, with parts broken away, of a tube and the plug shown in Figs. 1, 2 and 3 with the latter positioned in an end of the former to serve as a stopper while permitting its use, if desired, as a piston plug, and with the domed closure end relaxed;

35 Fig. 5 is a sectional view similar to Fig. 4 but showing the in-folding of the domed closure end with application of pressure thereto externally, a dot-dash line position of the so in-folded plug being indicated to illustrate its use as a piston plug;

Fig. 6 is an axial section to a smaller scale of 45 an ampule comprising a tube closed at one end and plugged at the other by the plug illustrated in Figs. 1 to 5 inclusive, showing a fragment of a piston post or thrust member associated needle of a syringe structure;

50 Fig. 7 is a view similar to Fig. 6 showing in-folding of the domed closure end of the plug when pressure is applied thereto by means of the piston post of the syringe after the needle has pierced therethrough;

55 Fig. 8 is a view similar to Fig. 6 showing the

relative position of the parts upon relief of the pressure applied in connection with the Fig. 7 illustration so as to provide aspirating action;

Fig. 9 is an axial section of a tubular structure or barrel in which the plug of the present invention is located to serve as a one-way valve partition structure, with another piston plug being employed to create hydraulic pressure in contained liquid to force the latter from the interior chamber of the crowned cupped plug through pierced slits in its domed closure end; and

Fig. 10 is a side elevational view of a modified form of the crowned cupped resilient plug of the present invention shown in Figs. 1 to 9 inclusive wherein the base sleeve section has a truly cylindrical external surface free from circumferential grooving; that view including in dotted lines a portion of a tube having a waist constriction with the plug serving at the constriction as a partitioning means.

Cupped rubber plugs have been commonly used in ampules and syringe barrel structures to serve as stoppers therefor and to act when desired as piston plugs for discharge of liquid contents when mounted in suitable syringe structures, as will be noted from my prior Patent 2,490,447 of December 6, 1949. However, when such plugs are closed off at the end by a transversely-extending wall, they are of limited use, since aspiration of a desired degree is not practically attainable therewith. Highly crowned plugs which permit a desired degree of aspiration have been used, but when the crown of such a plug projects from the end of a tubular barrel structure or ampule, external pressure thereagainst causes it to flop over or bulge laterally to beyond the edge of the tube, thus undesirably interfering with certain uses of the plug, such as for a piston plug. These and other difficulties of prior art attempts are efficiently eliminated by the crowned cupped resilient plug of the present invention, which additionally permits effective use thereof as a blocking or one-way valve partition at a point between the ends of tubular structures.

As will be seen from the drawing, in which like numerals identify similar parts throughout, an embodiment of the present invention illustrated in Figs. 1 to 8 inclusive may comprise a body 11 of resilient material, such as synthetic or natural rubber or gum and the like, having a substantially cylindrical base sleeve section 12 and a domed protruding closure end 13 circumferentially joined to the former at its outer end 14. As best seen in Fig. 3, the walls 15 of the base sleeve section 12 are relatively thick to be appreciably resistive to distortion while permitting limited diametrical constriction to allow a fluid-type fit into a tubular structure, such as a circular hole, tube or cylindrical barrel. The domed protruding closure end 13 is provided with a stiffened transversely-extending central section 16 to define between its margins and the outer end 14 of the base sleeve section 12 a substantially conical zone portion 17, which, as will be seen from Fig. 3, is formed of relatively thin stock so as to be of greater flexibility than both the central section and the base sleeve section. Preferably, the central section 16 is formed by a circular protruding rib 18 arranged about a circular, relatively thin-walled, transverse tip membrane 19, so that the latter is easily pierceable by a needle while serving as a part of the relatively rigid central section 16. However, it will be understood that all of the central section 16 may, if desired, be in the form of a relatively thick pad

of substantially uniform thickness, particularly if the use of the plug is such as not to require central piercing thereof by a needle or should certain resistance to such piercing be unobjectionable.

As indicated in Fig. 3, the outer surface of the zone 17 preferably has its generatrix, as represented by the dotted line 20, disposed substantially at an angle "X" of about 45° to the plug axis, as represented by a dot-dash line 21. It has been found, in accordance with the present invention, that 45° is about the minimum limit of that angle in order to assure elimination of any tendency for the domed protruding end 13 to flop over under external pressure or to bulge laterally to an interfering degree. It is to be understood that the domed protruding end 13 may, within the scope of the present invention, be flatter than that shown by way of example in the drawing so that angle "X" approaches to within a few degrees of 90° with the plug axis 21. However, the flatter the domed protruding end 13 is, the lesser is the aspirating action which is attainable by the plug. It will thus be seen that in the preferred embodiments the zone 17 is in the shape of the surface of a frustum of a right cone, but other shapes thereof which closely approach the same while possibly providing slightly curved walls in that zone, either convex or concave to a small degree, are contemplated within the scope of the present invention and the terminology used herein.

In the preferred embodiments shown in the drawing, the bore 22 of the base sleeve section 12 is preferably constricted or throated at 23 to assure an appreciable thickness of the walls 15, at least at that point, for attainment of the desired relative resistivity to distortion or rigidity. The bore 22 is flared out as it approaches the outer end 14 of base sleeve 12 so as to permit circumferential connection thereto of the base end of the frusto-conical section 17 at an appreciable diametrical distance from the axis 21, thereby assuring a fair width of the flexible zone to permit good flexing action. It will thus be seen from Fig. 3 that the chamber 24 provided within the crowned cupped resilient plug 11 is substantially bulbous.

In the structure shown in Figs. 4 and 5, tube 25 may be an end portion of a syringe barrel or an ampule of the type shown in my prior patent identified above, with one end closed by the plug 11 of the present invention. Assuming that the tube 25 is the cartridge sleeve of an ampule intended for use in a Cook type of syringe, as illustrated in U. S. Patent 1,661,818 of March 6, 1928, so as to serve as the barrel thereof, the crowned cupped plug 11 of the present invention serves as the closing piston plug in one end thereof. It is well understood in the art that in order to discharge liquid contents of such a barrel through the needle of such a syringe structure, such piston plug is forced to slide down therein by depression of a suitable plunger. In Fig. 5, responsive distortion of the present plug to such plunger action is illustrated. It will there be seen that with application of pressure externally to the protruding tip of the plug 11, as diagrammatically indicated by the arrow 26, the domed protruding closure end 13 is distorted inwardly with flexure of the zone 17. During such flexure of zone 17, there is no appreciable lateral bulging of the plug in the vicinity of the end 14 of base sleeve 12, or any of such degree as to cause the formation of a fold which would over-

lap the edge 27 of the tube 25 to such an extent as to interfere with piston sliding action thereof. Such piston action is illustrated in Fig. 5 by a dot-dash outline at 28, which represents the location of the plug when pushed inwardly the distance between the points 29 and 30. The infolding of the tip 13 has been exaggerated in Fig. 5 in order to avoid any possible confusion in the showing of that figure.

In Fig. 6, the tube 25 is illustrated as an ampule adapted to serve as the barrel of a syringe structure of the type illustrated in my above identified patent. Ampule tube 25 of Fig. 6 contains a body 31 of medicinal solution intended for hypodermic injection, with the end of the tube suitably closed off by plug 11 of the present invention. A portion of piston post or thrust member 32 of the syringe structure and the associated inner end 33 of a double-ended injection needle are shown with the latter being thrust into the membrane 19. After the syringe needle has been properly inserted into a patient's flesh, the domed end of the plug 11 will be depressed or in-folded, as shown in Fig. 7, by pushing the ampule 25 toward the post or thrust member 32. As a result, the space within the ampule will be reduced so as momentarily to discharge through the needle a small quantity of fluid contents. Then, upon relief of pressure against ampule 25, as shown in Fig. 8, the resiliency of the plug 11 will cause its domed end to protrude again with suction being created on needle 33, to provide a desired aspirating action.

The employment of the plug of the present invention as a valved partition in a tubular structure is illustrated in Fig. 9 wherein a portion of tube 125 is shown fitted between its ends with one of the plugs 11. The latter is preferably provided with a plurality of pierced slits 34-34 in the zone 17, such as by thrusting a needle therethrough at a plurality of points about the tip 16. As a result, when hydraulic pressure is applied in chamber 24 by forcing a piston plug 35 of usual construction into the tube in the direction of the arrow indicated, liquid 131 will be caused to bulge the domed end, as shown, with an attendant opening of the slits 34-34. Consequently, liquid is caused to pass through the partition plug via the open slits 34-34. Their location in the zone 17 is preferred since it will direct resulting jets of liquid against the inner walls of the tube 125, rather than axially to give a fountain action which may be undesirable. If, however, such fountain action is not objectionable, membrane 19 within the stiffening rib 18 may also be provided with a needle-pierced slit 134 to supplement the action of the slits 34-34. The opening of the slits 34-34 and 134 under hydraulic pressure applied internally of chamber 24 is, of course, caused by the stretching of the relatively thin flexible walls of zone 17 and the central membrane 19 as the domed end of the plug 11 is bulged under the application of pressure within the chamber, as is well illustrated in Fig. 9. Upon relief of hydraulic pressure with cessation of sliding motion of piston plug 35, the domed end of the piston plug 11 will relax so that the pierced slits 34-34 and 134 will naturally close by contraction of the resilient walls of zone 17 and membrane 19. Those slits will remain effectively closed against any pressure applied externally of the domed end since such application of external pressure will fold it inwardly, such as is indicated in Fig. 4, and in such distorted disposition, the needle-pierced slits remain effectively closed against passage of fluid.

In Fig. 10 is shown in full lines at 111 another embodiment of the plug of the present invention differing chiefly from that illustrated in Figs. 1 to 9 inclusive in a change in the base sleeve section 12 thereof. In the plug of Figs. 1 to 9 inclusive the base sleeve section 12 preferably is provided with a plurality of circumferentially arranged external grooves 36, 36 for a purpose well known in the art, while the base sleeve section 112 of the Fig. 10 plug is provided with a substantially true cylindrical surface 136. Such a change in the plug structure of the present invention is preferred when it is desired to use the same as a partitioning means in a tubular structure having a constricted waist, such as that indicated in dotted lines at 125 and 37 respectively in Fig. 10. The constricted waist 31, of course, may be so dimensioned as to serve either as a permanent seat for such a partitioning plug or as means intended only temporarily to retard sliding action of plug 111 upon application of pressure thereto.

It will thus be seen that the objects set forth above, among those made apparent from the preceding description, are efficiently attained and, since certain changes may be made in the above article, and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A crowned cupped resilient plug for tubular structures comprising a hollow, substantially cylindrical base sleeve section having relatively thick walls to be appreciably resistive to distortion while permitting limited diametrical constriction to allow fluid-tight fitting into a tubular structure; a domed, protruding closure end circumferentially joined to one end of said sleeve section; and a stiffened, transversely-extending, central section on said domed closure end defining between its margin and said sleeve section a substantially conical zone portion, said closure end zone being of greater flexibility than said central section and said sleeve section with the generatrix of the outer surface of said zone being disposed substantially at an angle to the axis of said plug of between about 45° and a few degrees less than 90°.

2. The crowned cupped resilient plug as defined in claim 1 characterized by the provision of said zone portion in substantially the shape of the surface of a frustum of a right cone with the thickness thereof being substantially less than the thickness of the walls of said base sleeve section and said stiffened central section to assure relatively greater flexibility.

3. The crowned cupped resilient plug as defined in claim 2 characterized by a disposition of the wall of said zone portion relative to the axis of said plug resulting from arrangement of the generatrix of its outer surface at an angle of about 45° to said axis.

4. The crowned cupped resilient plug as defined in claim 3 characterized by the provision of normally-closed, pierced slits in said domed closure end permitting said plug to serve as a

one-way valve with said slits opening under fluid pressure applied from within said base sleeve section and closing with in-folding of the domed closure and upon application of fluid pressure externally thereto.

5. A crowned cupped resilient plug for tubular structures comprising a body of resilient material including a base sleeve provided with relatively thick walls to assure relative rigidity; a relatively thin-walled, highly flexible, frusto-conical section circumferentially joined at its base to and protruding from one end of said sleeve with the generatrix of its outer surface arranged at an angle to the axis of said plug of between about 45° and a few degrees less than 90°; and a stiffer, transversely-extending, axially-located section closing off the outer smaller end of said frusto-conical section.

6. A crowned cupped resilient plug for tubular structures comprising a body of resilient material including a base sleeve provided with relatively thick walls to assure relative rigidity; a relatively thin-walled, highly flexible, frusto-conical section circumferentially joined at its base to and protruding from one end of said sleeve with the generatrix of its outer surface arranged at an angle to the axis of said plug of about 45°; and a stiffer, transversely-extending, axially-located section closing off the outer smaller end of said frusto-conical section.

7. A crowned cupped resilient plug for tubular structures comprising a body of resilient material including a base sleeve provided with relatively thick walls to assure relative rigidity; a relatively thin-walled, highly flexible, frusto-conical section circumferentially joined at its base to and protruding from one end of said sleeve with the generatrix of its outer surface arranged at an angle to the axis of said plug of between about 45° and a few degrees less than 90°; said frusto-conical section having normally-closed pierced slits therein to be opened by fluid pressure applied from within said base sleeve; and a stiffer, transversely-extending, axially-located section closing off the outer smaller end of said frusto-conical section.

8. A crowned cupped resilient plug for tubular structures comprising a body of resilient material including a base sleeve provided with relatively thick walls to assure relative rigidity; a relatively thin-walled, highly flexible, frusto-conical section circumferentially joined at its base to and protruding from one end of said sleeve with the generatrix of its outer surface arranged at an

angle to the axis of said plug of about 45°; said frusto-conical section having normally-closed pierced slits therein to be opened by fluid pressure applied from within said base sleeve; and a stiffer, transversely-extending, axially-located section closing off the outer smaller end of said frusto-conical section.

9. A crowned cupped resilient plug for tubular structures comprising a body of resilient material including a base sleeve having relatively thick walls to assure relatively high rigidity and with its outer surface being substantially cylindrical to be fitted into a tubular hole; a relatively thin-walled, highly flexible frusto-conical section circumferentially joined at its larger base end to one end of said sleeve and protruding therefrom with the generatrix of its outer surface arranged at an angle of about 45° to the axis of said plug; and a stiffer, transversely-extending tip portion closing off the outer, smaller end of said frusto-conical section with a protruding circumambient external stiffening rib thereon arranged about a relatively thin needle-pierceable area thereof.

10. A crowned cupped resilient plug for tubular structures comprising a body of resilient material including a base sleeve having relatively thick walls to assure relatively high rigidity and with its outer surface being substantially cylindrical to be fitted into a tubular hole, the bore of said sleeve being enlarged at its outer end; a relatively thin-walled, highly flexible frusto-conical section circumferentially joined at its larger base end to the outer end of said sleeve and protruding therefrom with the generatrix of its outer surface arranged at an angle of about 45° to the axis of said plug; and a stiffer, transversely-extending tip portion closing off the outer smaller end of said frusto-conical section with a protruding circumambient external stiffening rib thereon arranged about a relatively thin needle-pierceable area thereof.

11. The crowned cupped resilient plug as defined in claim 10 characterized by the shaping of the bore in said sleeve to provide near its inner open end a constricted throat with the walls of the bore gradually flaring from that constriction to the wider portion thereof at its outer end so that said frusto-conical section is of maximum width to provide for free flexing action thereof.
